FORGE FURNACE

James W. Vanderpool, Dedham, and Raymond E. Fiscus, Malden, Mass., assignors to Eastern Refractories Company, Inc., Boston, Mass., a corporation of Massachusetts

Application June 17, 1937, Serial No. 148,715

3 Claims. (Cl. 263—43)

This invention relates to an improvement in a forge furnace adapted to heat, reheat or temper iron, steel or any of the compounds or mixtures of metal containing iron as a base metal or as 5 an alloy as well as any non-ferrous metals which might be so treated.

The primary object of this invention is to provide a forge furnace so constructed that the metal is heated at or near the hearth and wholly within 10 the furnace, and that any pieces of metal which inadvertently get into the furnace can easily be recovered.

Further objects of the invention are to provide a furnace wherein only the coldest gases are exhausted, the hottest gases are brought in contact with the metal or the hearth, escape of the products of combustion through the loading door is eliminated, cleaning of the furnace is made easy, and high efficiency from the fuel standpoint is 20 maintained.

These and other objects will appear from a consideration of the following description of a furnace embodying this invention and of the accompanying drawings which form a part there- 25 of and in which

Fig. 1 is a perspective view of an installation including a furnace which embodies this invention;

Fig. 2 is a sectional plan view of such furnace taken through the metal loading door;

Fig. 3 is a transverse sectional view taken along the line 3—3 in Fig. 2;

Fig. 4 is a longitudinal sectional view taken along the line 4—4 in Fig. 3; and

Fig. 5 is a longitudinal sectional view taken 35 along the line 5—5 in Fig. 2.

The furnace 10 is supported in the usual manner by a frame 11 here shown as comprising a plurality of posts 15 and connecting cross bars 16 formed of angle bars and a platform 17. The 40 furnace 10 comprises a combustion chamber 20 and a stack 21. The chamber 20 includes a hearth 22 on which the metal is heated and has a lining 23 of suitable refractory material.

The fuel, oil, gas or the like, is fed into the 45 chamber 20 from tuyères (not shown) through inlet passages 25 and the used combustion gases pass from the chamber 20 through exhaust outlets 26 and flues 27 to the stack 21. The metal is placed on the hearth 22 through the loading inlet 28.

50 As shown in the drawings, the furnace is built on the down draft principle, the combustion gases entering near the top of the chamber and leaving at the bottom thereof. The inner face of the lining 23 is so formed that the gases are forced to follow the swirling path, indicated by the ar-

rows 29 in Fig. 4, from the top of the chamber downwardly along the front wall thereof, and rearwardly over the hearth 22 and upwardly along the rear wall.

The sides and bottom of the furnace have an 5 outer casing 30 of sheet metal and between the casing and the lining is an intermediate layer 31 of insulating material. The arch 35 of the furnace is preferably made removable, anchors 36 being inserted in the lining. The heads of the 10 anchors 36 receive I beams 37 extending across, and supported by, the frame 11 and the arch is thus firmly held in position. The lining above the loading inlet 28 is also reinforced by anchors 15 38 carried by posts 39 supported upon angle beams 40 extending across the frame. Additional anchors 41 carried by the casing 30 at the front and rear walls reinforce the lining at other points as shown in Fig. 5. When conditions require access to the chamber 20 as for repairs to the lining 23 20 or hearth 22, the arch 35 can easily be lifted by a crane or other hoisting apparatus attached to the I-beams 37, the layer 31 of insulation which forms the top of the furnace being cut to permit removing the arch. Access to the chamber is 25 thus afforded and the necessary work can easily be done.

The flues 27 are controlled by a damper 45 adjustably located at the base of the stack and thus the combustion in the chamber can be read- 30 ily regulated as desired. As shown in Fig. 4 the combustion gases are caused to travel downwardly along the front wall and inwardly at the metal loading inlet 28. Thus there is no danger that these gases will flow out of the chamber 35 through the inlet 28, and hence no air curtain or other protecting barrier need be provided as is usual in most forge furnaces.

It will be noted that as the gases travel in the 40 chamber, the gases which are hottest pass over the hearth 22 and heat the metal placed thereon. Since such gases have given up heat to the metal, they are now cold and drop out of the chamber through the outlets 26 at the rear end of the hearth. The remaining gases rise to the top of 45 the chamber where they mingle with the fresh gases entering the inlets 20 and the cycle is repeated.

While one embodiment of the invention has been shown and described, it will be understood 50 that the invention is not limited thereto and that the described embodiment may be altered or other embodiments may be made without departing from the spirit and scope of the invention as set forth in the following claims.

I claim:

1. A down draft forge furnace comprising a combustion chamber and a stack, said chamber having openings in a wall thereof near the top through which combustion gases are forced under pressure, and a loading opening in an opposite wall thereof near the bottom through which metal to be heated is introduced into the chamber, a hearth at the bottom of the chamber onto which the metal is fed through said last named openings, a plurality of openings in the bottom of the chamber adjacent the hearth, and lining material on the walls of the chamber so shaped at its inner surface that the gases entering the chamber are caused to travel downwardly past the loading opening to the hearth, thence over the hearth and in part upwardly, the remainder passing out of the chamber through the openings adjacent the hearth, flues connecting said last named openings to said stack and a damper for controlling the passage of the gases through the flues to the stack.
- 5
2. A down draft forge furnace comprising a combustion chamber and a stack, said chamber having openings in a wall thereof near the top through which hot combustion gases are forced under pressure, and a loading opening in an opposite wall thereof near the bottom through which metal to be heated is introduced into the chamber, a hearth at the bottom of the chamber onto which the metal is fed through said last-named openings, a plurality of openings in the bottom of the chamber adjacent the hearth, and lining material on the walls of the chamber so shaped at its inner surface that the gases entering the chamber are caused to travel downwardly past the loading opening to the hearth, and thence over the hearth toward the first-mentioned wall, the cooler portion of the gases passing out of the chamber through the openings adjacent the hearth, and the remainder of the gases rising to join the gases forced into the chamber, and flues connecting the openings adjacent the hearth to the stack whereby the cooler portion of the gases escape from the furnace.
- 10
3. A down draft forge furnace comprising a combustion chamber and a stack, said chamber having openings in a wall thereof near the top through which hot combustion gases are forced under pressure, and a loading opening in an opposite wall thereof near the bottom through which metal to be heated is introduced into the chamber, a hearth at the bottom of the chamber onto which the metal is fed through said last-named openings, a plurality of openings in the bottom of the chamber adjacent the hearth, and lining material on the walls of the chamber so shaped at its inner surface that the gases entering the chamber are caused to travel downwardly past the loading opening to the hearth, and thence over the hearth toward the first-mentioned wall, the cooler portion of the gases passing out of the chamber through the openings adjacent the hearth, and the remainder of the gases rising to join the gases forced into the chamber, and flues connecting the openings adjacent the hearth to the stack whereby the cooler portion of the gases escape from the furnace.
